UNITED STATES PATENT OFFICE.

JAMES H. STEELE, OF EUGENE, OREGON; ALICE L. STEELE EXECUTOR OF SAID JAMES H. STEELE, DECEASED.

CABLE-CLAMP.

1,277,768.

Specification of Letters Patent. Patented Sept. 3, 1918.

Application filed March 1, 1917, Serial No. 151,758. Renewed June 4, 1918. Serial No. 238,219.

To all whom it may concern:

Be it known that I, JAMES H. STEELE, a citizen of the United States, residing at Eugene, in the county of Lane and State of Oregon, have invented certain new and useful Improvements in Cable-Clamps, of which the following is a specification.

My invention relates to improvements in cable grips, and it consists in the constructions, combinations, and arrangements herein-described and claimed.

An object of my invention is to provide a cable grip including a cable engaging block and cap interengageably held by an arrangement of mortise and tenon grooves, the cap supporting a pivoted cable clamp by means of which the block and cap are clamped into tight engagement to clamp the cable.

Another object of my invention is to provide a cable grip which may instantly be removed from engagement with the cable and moved to another position thereon so that the cable may be grasped at any point at will.

Other objects and advantages will appear from the following specification, reference being had to the accompanying drawing, in which:

Figure 1 is a side elevation showing the cable clamp in position on a cable, the pivoted clamp member being shown in an open position in dotted lines.

Fig. 2 is a detail central longitudinal section of a portion on the cable grip.

Fig. 3 is a plan view of the parts shown in Fig. 1, and

Fig. 4 is a cross-section on the line 4—4 of Fig. 1.

In carrying out my invention I provide a shoe or block 1 which is substantially of the configuration shown in Fig. 1. The block 1 is provided with a longitudinal semicircular groove 2 in which the cable 3 is adapted to rest. The block 1 is provided at each side of the groove 2 with a plurality of lugs or tenons 4. The tenons 4 are disposed at an angle which is directed rearwardly for a purpose presently to appear.

The forward end of the block 1 is partially rounded as at 5 and forms a clamp engaging surface. A cap 6 cooperates with the block 1 and is also provided with a semicircular longitudinal groove 7 on its under face. Mortises 8 are formed at the sides of

the cap 6 and are adapted to receive tenons 4 of the block 1. In providing the tenons 4 on the block 1, it will readily be seen that spaces or mortises 9 are consequently formed at the sides of the block 1 between the tenons 4. The mortises 9 are occupied by coacting tenons 10 on the cap 6 when the block and cap are assembled and clamped into position on the cable 3.

Disposed on the forward end of the cap 6 is a bearing lug 11 which is apertured at its end to receive a pivotal bolt 12 of a cable clamp 13. The end of the cable clamp 13 adjacent to the pivot 12, is bifurcated as clearly shown in Fig. 3 so as to provide a pair of clamping feet 14 which are correspondingly rounded that they may easily engage the similarly rounded surface 5 on the forward end of the block 1.

The forward end of the cable clamp 13 is provided with an eye 15 which forms the hitch which may be engaged by a suitable hook when it is desired to pull the cable 3. It should be understood with reference to the particular formation of the mortises and tenons of the block 1 and cap 6 respectively, that these mortises and tenons may be formed in any desirable manner, the feature to be preserved being a rearward inclination of the vertical surfaces thereof. In other words the particular number or mortises and tenons on either side is immaterial, and the number thereof may be either even or odd.

Having thus described the construction of the device the operation and manner of its application is as follows:

It frequently occurs in contracting work that a cable structure 3 is to be pulled. An effective cable grip is at such a time a desirable and necessary implement to have at hand. With the use of my device the lower shoe or block 1 is simply laid to meet the cable 3. The cable clamp 13 is swung upwardly into position shown in dotted lines in Fig. 1, and the cap 6 is superposed on the block 1, the respective rearwardly inclined mortises and tenons being fitted together.

The cable clamp 13 is now swung downwardly on its pivot 12 until the clamp members 14 engage the rounded forward surface 5 of the block 1. This point of engagement will now act as a fulcrum and a pull on the forward end of the cable clamp 13 through the medium of a connection in the eye 15, 110

will serve to pull the cap 6 forwardly and into tight engagement with the respective surfaces of the upstanding tenons of the block 1. Bearing this forward movement of 5 the cap 6 through the medium of a pull on the cable 13 in mind, it will be readily seen that the engagement of the tenons 10 of the cap 6 the rearwardly inclined surfaces of the tenons 4 of the block 1, will cause the 10 cap 6 to move downwardly and therefore grip the cable 3 tightly between the block 1 and the cap 6.

Should it be desired to change the point of application of the cable grip, it is simply 15 necessary to swing the cable clamp 13 up to the dotted line position shown in Fig. 1, when the cap 6 and block 1 may readily be disengaged and moved to another position on the cable 3. Having thus described the 20 construction of the cable grip which might be said to be that of a generally preferred form, it should be also understood that various modifications in the construction thereof may be made without departing from the 25 spirit of the invention or the scope of the claims.

I claim:—

1. A cable grip including a block having a semicircular longitudinal cable receiving 30 groove, said block having a rounded surface and being provided with rearwardly extending tenons, a cap having a semicircular longitudinal groove and forwardly extending mortises, a bearing lug on the cap, a cable 35 clamp fulcrumed on the lug, said clamp having a bifurcated portion forming a pair of feet adapted to engage the rounded front surface of the block, said clamp also including a hitching eye.

40 2. A cable grip comprising a block, a cap positioned upon said block, a bearing lug projecting from said cap, a cable clamp pivotally mounted upon said lug, said cable

clamp having a foot projecting beyond one end thereof, said foot releasably engaging 45 said block for urging said block into a clamping engagement with said cap when said cable clamp is swung in one direction so that a cable interposed between said block and cap will be firmly gripped.

3. A cable grip comprising a block, a cap positioned upon said block and having a bearing lug projecting therefrom, said block having registering longitudinally extending 50 grooves, said lug having a bearing bolt, a cable clamp pivotally mounted upon said bolt and having a bifurcated portion for forming a pair of spaced feet, said feet being adapted to bear upon said block for bringing the same into engagement with said cap, 55 thus causing a cable interposed between said block and cap to be firmly gripped, and the bifurcated portion of said lever clamp providing space for the projection of the cable extending therebetween.

4. A cable grip comprising a block, a cap positioned upon said block, guiding means formed upon said block and cap for directing the same into engagement with each other, said block and cap having registering 70 grooves, a cable clamp pivotally mounted upon said cap, said cable clamp having a bifurcated portion thereby forming spaced feet, said bifurcated portion registering with the ends of said grooves, and said feet bearing upon said block for urging the same toward said cap, thus causing a cable interposed between said block and cap to be firmly gripped.

In testimony whereof I affix my signature 75 in presence of two witnesses.

JAMES H. STEELE.
